UNITED STATES PATENT OFFICE

VERN WYSONG, OF PERU, INDIANA, ASSIGNOR TO PERU BASKET CO., OF PERU,
INDIANA, A CORPORATION OF INDIANA

IRONING BOARD

Application filed January 10, 1930. Serial No. 419,958.

My invention relates to ironing boards and it is the object of the invention to provide an ironing board having novel features of construction and inexpensive to manufacture.

5 A further object is to produce an ironing board which can be opened in a simple operation and when opened constitutes a rigid board without bracings on the legs that heretofore have been necessary.

10 Referring to the accompanying drawings which are made a part hereof and on which similar reference characters indicate similar parts,

Figure 1 is a side elevation of my invention 15 in open position,

Figure 2, a bottom plan view showing the ironing board folded, and

Figure 3, a cross-sectional view on line 3—3 of Figure 1.

20 In the drawing reference character 10 indicates the table portion of an ironing board of conventional shape having secured to the bottom parallel to the large end of the table portion a clevis 11 provided with a plurality 25 of depending lugs 12 and 13. A pair of legs 14 is pivotally secured to the inner pair of depending lugs 12 and a pair of braces 15 is pivotally secured at one end to the other depending lugs 13 and the lower ends pivotally 30 fixed to the outside of its corresponding leg in such a manner as to permit the legs 14 to be folded against the board. A second pair of braces 16 is pivotally fixed to the inside of the legs 14 and extends diagonally toward 35 the center of the board when in open position. The free ends 17 of the braces 16 are swingingly connected by a U-shaped hook 18 which is slidably secured to the board portion by means of a long metal strip 19 fixed at

40 each end to the under side of the board. The undersides of the leg braces 16 are also connected by a slotted metal band 20 which allows the braces 16 and also the legs 14 to spread when the board is opened and acts as 45 a closing device on the legs when collapsed. A third leg 21 is pivotally secured to a pair of depending lugs 22 near the center of the board between the braces 16 and the band 20 and extending obliquely downward when in

50 open position. To prevent undue wear by

contact of the slotted band 20 a metal plate 23 is fixed to the leg. At the pivoted end of the leg 21 and back of the lugs 22 a strip 24 is secured on which the end of the leg may rest removing unnecessary strain on the lugs and tending to strengthen the board. In order to hold the leg 21 in open position a reinforced notch 25 is located near the free end on the upper side of the leg into which the brace rod 26 enters. The said brace rod 26 is pivotally hinged by loops 27 at the clevis 11. The brace rod is prevented from becoming displaced by a metal strip 28 secured above the notch 25 which permits the brace to slide and of such a length as to allow closing and opening of the board. A bar 29 is pivoted at its center on the leg 21 and serves as a latch to hold the legs in folded position as shown in Figure 2.

55 It will be obvious to those skilled in the art that various changes may be made in my device without departing from the spirit of the invention and therefore I do not limit myself to what is shown in the drawings and described in the specification, but only as indicated in the appended claims.

60 Having thus fully described my said invention, what I claim as new and desire to secure by Letters Patent, is:

1. An ironing board comprising a table portion, a pair of legs pivotally attached to the table portion near its end, a pair of braces pivoted to the inside of said legs and extending diagonally toward the other end of said table portion and being slidably connected thereto, a third leg pivoted to the board near its center and having a notch near its lower end, a hinged brace rod secured to said table portion and extending over said third leg and having means adapted to engage the said notch and hold said third leg in a fixed position for maintaining said board in open position, a band on the underside of said pair of braces, a bar pivoted at its center to the underside of said third leg, said last mentioned band and bar serving as a means to hold said legs in fixed position when closed, substantially as set forth.

2. An ironing board comprising a table portion, a pair of legs pivotally attached to the

table portion near its end, a pair of braces pivoted to the inside of said legs and extending diagonally toward the other end of said table portion and being slidably connected thereto, a third leg pivoted to the board near its center and having a notch near its lower end, a hinged brace rod secured to said table portion and extending over said third leg and having means adapted to engage the said leg in a fixed position for maintaining said board in open position, and a band connected at its ends to each of said pair of braces said band having lost motion connection with said braces to allow them to separate and to limit the separation thereof, substantially as set forth.

3. An ironing board comprising a table portion, a clevis secured to said table portion having depending lugs, said lugs having supporting members and braces pivotally secured thereto, a separate supporting member pivotally secured to said table portion near its center, a pair of braces extending from said supporting members, said braces having a hook connecting their free ends and slidably secured to the under side of the table portion, a band connected at its ends to said pair of braces, said band having lost motion connection with said braces to allow them to separate and to limit the separation thereof, and means for holding said supporting members in stationary position when collapsed, substantially as set forth.

In witness whereof, I have hereunto set my hand at Peru, Indiana this sixth day of January, A. D. nineteen hundred and thirty.

VERN WYSONG.
